SHEET METAL STRUCTURE

Martinus Jacobus Charles Johanns, Rotterdam,
NetherlandsApplication August 26, 1938, Serial No. 226,898
In the Netherlands February 8, 1936

7 Claims. (Cl. 189—64)

My invention relates to sheet metal sections or structures particularly to structures for frames of windows and doors.

One object of my invention is sheet metal structures or sections comprising a straight main web or ledge connected substantially at right angles at one or both edges to two double flanges which consist of parallel legs spaced apart. The outer legs of one or both flanges are continued to form second straight webs or ledges which are smaller than the main web and terminate in re-entrant flanges which are extended to a point substantially spaced from the level of the bend of the associated double flange.

Other and further objects of the invention will be hereinafter set forth and the novel features thereof defined by the appended claims.

Several embodiments of my invention are shown in the accompanying drawings. These also illustrate various features which can be conveniently combined with the principal features of the invention.

Figs. 1-8 show various structures according to the invention in cross-section.

Figs. 9-12 show several applications of structures according to Figs. 1-8 in cross-section.

Figs. 13-15 show various elements to be used in combination with structures according to the invention.

Fig. 16 shows another application of a structure according to the invention in cross-section.

Figs. 17 and 18 show further elements to be used in combination with structures according to the invention.

Fig. 19 shows another application of structures according to the invention in cross-section.

Fig. 20 shows a further structure according to the invention in cross-section.

Fig. 21 shows another application of structures according to the invention.

Figs. 22-24 show in cross-section and in front view further elements to be used in combination with structures according to the invention.

Fig. 25 shows a further structure according to the invention in cross-section and Fig. 26 shows another application of a structure according to the invention in cross section.

The structures according to the invention shown in Figs. 1-8 consist of metal and comprise a main web 3 having on both sides of it double flanges 1 standing vertically to the web 3, which are obtained by the groove-forming bends 2 so that the legs of the respective flanges are parallel and spaced apart. In Figures 1 and 2 both outside legs of the flange-shaped grooves have

been extended to form smaller webs 6 and re-entrant flanges 4 running parallel to the associated double flanges 1 and terminating at points substantially spaced from the level of the bends of the double flanges. In Fig. 2 the extension of the one leg is longer than the extension of the other as the figure clearly shows. The terminal points of these flanges 4 are provided with in-turned lips 5.

In Figs. 3, 4 and 5 only one of the outside legs 10 has been extended and bent to form a re-entrant flange 4 and a lip 5. As seen in the figures, the outer leg of each double flange is extended below the leg, so that the second web 6 of the groove formed by the re-entrant flange 4 is parallel to 15 the main web 3 but is spaced therefrom. Alternatively the second web 6 can also, as seen in the Figures 2, 5 and 7, lie level with the main web 3. As will appear hereinafter, advantages accrue by the provision of the lips 5 which are obtained 20 by bending the metal inwardly and rectangularly to the flanges 4.

By the bends according to the invention a flexible but strong construction is obtained which has a considerable resistance against bending or 25 deflection.

In Fig. 8 the lip 5 is slightly dovetailed. In the same manner, as shown in Figs. 3, 4 and 5, only one leg is extended, the other outer leg being provided in an arbitrary manner with a reinforcement 30 7 or the like.

In Figs. 9-12 and Figs. 16-25 some applications of constructions according to the invention are shown. In Fig. 9 constructions according to Figs. 6 and 7 are applied to swing arms 44 the 35 bottom sill of which is shown. In the recesses formed by the webs 6 and re-entrant flanges 4 strips 10 of india rubber or other sound and shock absorbing material are inserted.

In the application of the invention illustrated 40 in Fig. 9 a resilient glass holder 16 is inserted and affixed in the groove 2 which is formed by the two legs of the double flange 1.

If no special strips of india rubber or the like are provided (Fig. 10) nevertheless an elastic 45 closing is obtained and shocks are prevented by the flexible flanges 4 and lips 5.

In Fig. 10 which also presents a bottom sill, an anchor 12 is shown, provided with a bit or projection 13 which engages the bead 7, to secure 50 the construction in place.

In Figure 7 an embodiment of the invention is shown in which the outside leg of one of the double flanges, instead of being formed into the re-entrant flange 4, is bent according to the inven- 55

tion to form a small element 9 running parallel with the web 3 and an element 8, which is slightly inclined relative to the web 3. The element 8 ends preferably in an upstanding lip or joggle 5 which is approximately vertical to the plane of the web 3.

In Fig. 9 the upper section is constructed as indicated in Fig. 7, the element 8 serving as a drip edge. In the lower structure the small element 9 is omitted and the part 8 serves as a condensation gutter, the rim of which is formed by the lip 5. In Fig. 10, the lower section is constructed as shown in Fig. 4. The small tubes or channels 11 shown in Figs. 9 and 10 serve as outlets for condensation water.

In Fig. 13 a glass support 16 is shown which can be held in its position by one of the double flanges as illustrated in Fig. 9. The bent portions 17 of the support 16 cause the necessary grip in the double flange and a part 18 serves as fastening means.

Fig. 11 shows how a structure according to the invention can be used to secure hollow plates, the structures employed being those according to Fig. 5. One of the structures is secured by an anchor 14 which is inserted in the groove between the legs of a double flange.

Structures according to Fig. 2 may be used for securing a fixed window or a wall. (See Fig. 12.) The re-entrant flanges 4 and lips 5 serve as a more or less flexible clamping device around an anchor 15. When, as indicated in this figure, wooden glass securing beads are used, the part 18 of the glass support 16 (see Fig. 13) is driven in the wood as shown in Fig. 12. Consequently the glass-securing beads can be secured against displacement without fastening screws.

Another resilient glass support 22 is shown in Fig. 15. As shown in Fig. 10 this glass support is inserted in the groove which is the nearest to the glass groove.

In Fig. 16 a bottom sill of a door is illustrated with a structure according to Fig. 5 applied thereto. The recess formed between the re-entrant flange 4 and the outer leg of the double flange 1 accommodates an india rubber strip 10 to secure an airproof and at the same time soundless closing.

24 is an insulating covering held by panel plates 23 which are inserted in grooves 2 of the structure.

For large structures a stiffening element 25 as shown in Fig. 17 for the stiffening of the corners could be affixed, for example by welding, in the 55 grooves formed between the legs of the double flanges in order to prevent deflection. Fig. 18 shows such a construction.

A further advantage of the construction according to the invention is shown in Fig. 19.

60 In Fig. 19 structures according to Fig. 3 have been applied for the jointing of a wall to a metal girder 37. The grooves forming the flanges contain the plates building up the wall. One of the flanges has been fastened to the girder 37 by means of bolts 26. These are enclosed within the recess formed by the re-entrant flange 4 and the lip 5 and therefore are invisible. Furthermore the flange 4 serves as a strong support which prevents deflection. On the inside, an insulating 70 covering 24 is brought against the panel plate 23 which is located in and held by the groove 2 formed between the legs of the double flange 1 of the section. The covering is also held fast by strips 27 fixed in the other groove 2. As is further schematically indicated in the figure, a

masonry or the like wall can be provided adjacent to the insulation. An insulating section 28 has been laid against the girder 37 and is located at one end in a groove 2 of another section and at the other end is supported by the lip 5 of the first section from which again another advantage of the section according to the invention appears.

In Fig. 19 there is also indicated how, by applying structures according to the invention, a window 10 43 can be affixed to the wall.

An L-shaped fastening strip 29 is affixed to the girder 37 by means of a screw 30 and clamps the section which holds fast the insulating element 28.

Also for the joining of parts to a wall (partition wall) the construction according to the invention can be of advantage. An example of such a construction is given in Fig. 21, in which structures according to Figs. 3 and 5 are employed. Both sections and the parts of the wall can, by means of the construction of the sections according to the invention, be kept together and in the grooves 2 formed by the double flanges, the panel plates 23 are placed. Hence it is not necessary to use screws or the like.

In Fig. 22 the manner in which an arm 34 (see Fig. 23) can be fixed to the structure according to Fig. 5 is indicated. The perpendicular flange 35 is partially removed.

In Fig. 26 there is shown the manner in which a structure according to the invention, when used with an india rubber strip 10, can be employed in conjunction with a known section.

Further constructional features of structures 35 according to the invention are illustrated in the Figures 20, 24, and 25.

In Fig. 20 the lip 5 is doubled to form a bead, the inner edge of which faces the re-entrant flange 4. The doubled lower portion is designated by 40. Furthermore a strip of flexible material 41 is affixed, by means of which the inner edge of the bead is concealed.

In Fig. 25 the beaded portion 7 of the other leg has also a doubled upper edge 40.

It is preferable to shape the beading in such a manner that the beading edge forms a hole or ear, as indicated in Fig. 24. In this case the doubled portion 40 is bent into a bevel and forms a curve 42. The beveling may serve to hold a flexible india rubber strip or the like in position. This is especially of advantage if, in order to get a good deflection, the rubber strip or the like is longer than the depth of the recess, as shown in Fig. 20, so that the strip stays somewhat bent.

Having now particularly described and ascertained the nature of my said invention and in what manner the same can be performed, I declare that what I claim is:

1. A sheet metal closure structure, comprising a substantially straight main web, two double flanges extending in the same direction relative to said main web substantially at a right angle to said web, shaped by bending off two longitudinal sides of said main web, each of said double flanges consisting of an inner and an outer leg parallel to and spaced from each other, thus forming a groove between each two legs, at least one of said outer legs being extended beyond the plane of said main web and bent off substantially at an angle of 180° thus forming a second groove in an opposite direction to said first groove between said outer leg and its extension, said extension terminating at a point beyond the bottom of said first groove and an inturned lip at 75

the end of said extension, said lip being arranged substantially at a right angle to said grooves.

2. A sheet metal structure according to claim 1 in which the bottom of said second groove is parallel to the bottom of said first groove.

3. A sheet metal closure structure consisting of a combination of two oppositely arranged units each comprising a substantially straight main web, two double flanges extending in the same direction relative to the plane of said main web substantially at a right angle to said web, shaped by bending off the two longitudinal sides of said main web, each of said double flanges consisting of an inner leg and an outer leg parallel to and spaced from each other thus forming a groove between each two legs, at least one of said outer legs being extended and bent off substantially at an angle of 180° thus forming a second groove in an opposite direction to said first groove between said outer leg and its extension and an inturned lip at the end of said extended outer leg, said lip of each unit intimately engaging the opposite outer leg of the opposed unit.

4. A sheet metal closure structure consisting of a combination of two oppositely arranged units each comprising a substantially straight main web, two double flanges extending in the same direction relative to the plane of said main web substantially at a right angle to said web, shaped by bending off the two longitudinal sides of said main web, each of said double flanges consisting of an inner leg and an outer leg parallel to and spaced from each other thus forming a groove between each two legs, at least one of said outer legs being extended and bent off substantially at an angle of 180° thus forming a second groove in an opposite direction to said first groove between said outer leg and its extension, an inturned lip at the end of said extended outer leg, said lip of each unit intimately engaging the opposite outer leg of the opposed unit and including a packing inserted between the outer leg, its extension and said lip at the end of said extension of one unit and the outer leg of the opposed unit thus securing said packing in its place.

5. A sheet metal closure structure consisting of a combination of two oppositely arranged units each comprising a substantially straight main web, two double flanges extending in the same direction relative to the plane of said main web substantially at a right angle to said web, shaped by bending off the two longitudinal sides of said main web, each of said double flanges consisting

of an inner leg and an outer leg parallel to and spaced from each other thus forming a groove between each two legs, one of said outer legs being extended and bent off substantially at an angle of 180° thus forming a second groove in an opposite direction to said first groove between said outer leg and its extension, an inturned lip at the end of said extended outer leg and a flange extending outwardly from said other outer leg thus forming a condensation channel, said lip of each unit engaging the opposite outer leg of the opposed unit.

6. A sheet metal closure structure for window frames including an arbor comprising a substantially straight main web, two double flanges extending in the same direction relative to said main web substantially at a right angle to said web, shaped by bending off two longitudinal sides of said main web, each of said double flanges consisting of an inner and an outer leg parallel to and spaced from each other thus forming a groove between each two legs, each of said outer legs being extended and bent off substantially at an angle of 180° thus forming a second groove in an opposite direction to said first groove between said outer leg and its extension, said extensions terminating at a point beyond the bottom of said first grooves, an inturned lip at the end of each of said extended outer legs, said in-turned lips engaging said arbor thus securing said sheet metal structure to said arbor.

7. A sheet metal closure structure for window frames including an arbor comprising a substantially straight main web, two double flanges extending in the same direction relative to said main web substantially at a right angle to said web, shaped by bending off two longitudinal sides of said main web, each of said double flanges consisting of an inner and an outer leg parallel to and spaced from each other thus forming a groove between each two legs, each of said outer legs being extended and bent off substantially at an angle of 180° thus forming a second groove in an opposite direction to said first groove between said outer leg and its extension, said extensions terminating at a point beyond the bottom of said first grooves, an inturned lip at the end of each of said extended outer legs, one of said extended outer legs extended beyond the plane of said main web before being bent off, said in-turned lips engaging said arbor thus securing said sheet metal structure to said arbor.

M. J. C. JOHANNES.
